Primary Examiner — Sharon S Oum(74) *Attorney, Agent, or Firm* — Dickinson Wright PLLC;
Andrew D. Dorisio(57) **CLAIM**

The ornamental design for a fan, as shown and described.

DESCRIPTION

FIG. 1 is a bottom perspective view of my design for a fan;
FIG. 2 is a top perspective view of the fan;
FIG. 3 is a front view of the fan, the rear view being a mirror image thereof;
FIG. 4 is a left side view of the fan, the right side view being a mirror image thereof;
FIG. 5 is a top view of the fan; and,
FIG. 6 is a bottom view of the fan.
The broken line depictions of portions of the fan form no part of the claimed design.

1 Claim, 6 Drawing Sheets(56)
